Richard Oliver.

ATTORNEY

UNITED STATES PATENT OFFICE.

CLINTON D. KEAGY, OF NEW CASTLE, PENNSYLVANIA.

DISINFECTING DEVICE.

1,253,603.

Specification of Letters Patent. Patented Jan. 15, 1918.

Application filed November 13, 1916. Serial No. 131,142.

To all whom it may concern:

Be it known that I, CLINTON D. KEAGY, a citizen of the United States, residing at New Castle, in the county of Lawrence and 5 State of Pennsylvania, have invented certain new and useful Improvements in Disinfecting Devices, of which the following is a specification.

This invention relates to a disinfecting 10 device and more particularly to a device for retaining a disinfectant within the money container of a cash box or cash register whereby all of the coins and currency within the container may be thoroughly disinfected. 15 The principal object of the invention is to provide the cash drawer of a cash box or a cash register with a plurality of plates having a series of perforations for permitting the fumes from the disinfectant to circulate through and around the money while, 20 at the same time, the disinfectant device occupies a minimum space within the money drawer.

As a further object of the invention the 25 covers are arranged above a plurality of layers of absorbent material such as blotting paper or the like and which are saturated with any suitable disinfectant.

A further object of this invention is the 30 provision of a disinfecting device which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is 40 illustrated the preferred form of my invention, in which;

Figure 1 is a top plan view of a money drawer showing my invention applied thereto.

Fig. 2 is a section on the line 2—2 of Fig. 1.

Fig. 3 is a top plan view of a modified form of the invention.

Fig. 4 is a section on the line 4—4 of Fig. 3.

Fig. 5 is a transverse section through a money drawer showing my invention applied to the side walls thereof.

Fig. 6 is a section on the line 6—6 of Fig. 5.

Referring to the drawing, wherein is illus-

trated the preferred form of my invention, and in which like numerals of reference indicate corresponding parts throughout the several views, the preferred form of the invention, as described in Figs. 1 and 2, discloses a money drawer 1 having a plurality of currency compartments 2 formed in its rear portion and which are spaced apart by the partitions 3. The forward portion of 60 the drawer is occupied by the coin container which has a plurality of the usual cups or depressions 4 into which the coins are deposited.

As clearly shown by Fig. 2 of the drawing, 70 the currency compartment 2 is provided with a receptacle 5 of substantially rectangular formation and adapted to fit snugly within each compartment 2. The depth of the receptacle 5 is sufficient to receive a plurality of strips 6 of absorbent material such as blotting paper or the like and these strips are saturated with any suitable disinfectant fluid. The receptacle 5 is provided with a cover plate 7 which has a plurality of ordinarily arranged concaved portions in its upper surface for providing a plurality of dished portions 8. Each concaved portion 8 has a plurality of apertures through which the fumes from the strips 6 are permitted to 80 pass into the compartments 2 whereby the currency arranged within the compartments may be thoroughly disinfected. The concaved or dished portions 8 are provided for the purpose of permitting the disinfecting 85 liquid to be poured through the apertures when the strips of absorbent material 6 become dry. By reason of this arrangement of the depressed portions 8, the liquid may be poured into the concaved portions and 90 thus evenly distributed over the strips 6.

In Figs. 3 and 4 of the drawing I have illustrated my invention as applied to a drawer having its whole bottom surface covered. In this instance the receptacle 9 is 100 mounted on the bottom of the whole drawer and is of shallow depth for receiving two or more sheets of blotting paper 10 which are saturated with the disinfectant. This receptacle 9 is also provided with a cover plate 11 adapted to be disposed within the drawer and completely cover the receptacle 9. A plurality of concaved portions 12 are each provided with a series of apertures for permitting the disinfectant fumes to pass 105 into the upper portion of the drawer.

In Figs. 5 and 6 the front or rear wall of

the drawer is employed to mount the disinfecting device and, in this instance, the receptacle 13 is fastened in any preferred manner to the front or end of the drawer. The 5 strips of blotting paper or absorbent material 14 are arranged within the receptacle in edgewise position and are held in place by the plate 15 having the concaved portions 16 through which the apertures are formed for

10 permitting the fumes of the disinfectant to pass into the drawer. This construction permits the drawer to be provided with this disinfecting device when the drawer or register is being manufactured.

15 I claim:

1. A disinfectant device comprising a receptacle of shallow depth and adapted to be fitted in a money drawer, a plurality of strips of disinfectant material arranged 20 within the receptacle, and a retaining plate carried by the receptacle and provided with a plurality of apertures, certain portions of the said cover plate being concaved, the said openings being extended through the 25 concaved portions.

2. A disinfectant device for a money drawer comprising a receptacle of shallow depth adapted to be mounted in the money drawer, a plurality of strips of absorbent 30 material arranged within the receptacle in

superposed relation and saturated with a disinfectant liquid, a retaining plate mounted on the receptacle and covering the said strips, the said plate having a plurality of concaved portions arranged at regular intervals on its upper surface, the concaved portions being provided with a plurality of perforations to permit of the escape of the fumes from the said disinfectant liquid. 35

3. A disinfectant device comprising a receptacle of relatively shallow depth and having a plurality of superposed strips of disinfectant material arranged therein and completely covering the bottom thereof, a retaining plate mounted upon the receptacle 40 and covering the said strip and provided with a plurality of concaved portions having their depressed surfaces engaged with the uppermost of the said strips, the said depressed portions being perforated to permit the escape of the fumes from the strips of disinfectant material at the point where they are engaged by the said depressed portions of the retaining plate. 45

In testimony whereof I affix my signature in presence of two witnesses.

CLINTON D. KEAGY.
